UNITED STATES PATENT OFFICE.

WILLIAM H. SMITH, OF BUFFALO, NEW YORK, ASSIGNOR TO JOIN R. KEIM, OF NEW YORK, N. Y.

DESIGN FOR AN AXLE-FRAME FOR MOTOR-VEHICLES.

SPECIFICATION forming part of Design No. 33,650, dated December 4, 1900.

Application filed November 9, 1900. Serial No. 35,984. Term of patent 14 years.

To all whom it may concern:

Be it known that I, WILLIAM H. SMITH, a citizen of the United States, residing at Buffalo, in the county of Erie and State of New York, have invented and produced a new and original Design for Axle-Frames for Motor-Vehicles, of which the following is a specification, reference being had to the accompanying drawing, forming a part thereof.

10 This design relates to the configuration of an axle-frame for motor-vehicles.

The accompanying drawing is a perspective view of an axle-frame for vehicles embodying my design.

15 The leading feature of my design consists of the peculiar shape of the steering-axle and driving-axle arranged at the front and rear ends of the axle-frame.

As shown in the drawing, the steering-axle 20 consists of a lower straight transverse bar A, an upper straight transverse bar B, which is arranged centrally above the lower bar A and parallel therewith, vertical side bars or posts C C, extending upwardly from the lower bar

25 A to the outer ends of the upper bar B, an intermediate upright bar or post E, extending upwardly from the central part of the lower bar to the central part of the upper bar, and inclined braces F, extending downwardly 30 from the upper ends of the side posts C C to the outer ends of the lower bar A. Each end of the lower bar A is provided with a bifurcated bearing g.

The rear axle consists of two lower straight 35 transverse bar-sections H H, which are arranged in line, an upper straight transverse bar I, which is arranged centrally over the inner ends of the lower bar-sections H H and parallel therewith, vertical side bars or posts

J J, which extend upwardly from the middle parts of the lower bar-sections H H to the outer ends of the upper bar I, inclined braces k k, extending downwardly from the upper ends of the side posts to the outer ends of the lower bar-sections H H, a rearwardly-curved 45 arch L, connecting the inner ends of the lower bar-sections on the rear sides thereof, two short longitudinal bars m m, projecting forwardly from the inner ends of the lower bar-sections H H, a short transverse bar n, connecting the front ends of the longitudinal bars m m, and inclined braces o o, extending from the upper transverse bar I downwardly to the front ends of the longitudinal bars m m. Each of the lower bar-sections H H is 55 provided at its inner and outer ends with circular bearings p p'.

Q Q represent the main longitudinal side bars of the axle-frame, which are connected at their front ends to the upper ends of the 60 side posts of the steering-axle and at their rear ends to the upper ends of the side posts of the driving-axle.

R represents inclined braces extending from the main longitudinal side bars Q Q to 65 the outer ends of the lower transverse bars A and H H of the steering and driving axles.

What I claim is—

The design for an axle-frame for motor-vehicles, substantially as herein shown and 70 described.

Witness my hand this 16th day of October, 1900.

WILLIAM H. SMITH.
